EDGAR K. HAND, OF CHICAGO, ILLINOIS, ASSIGNOR OF ONE-THIRD TO CHARLES TURNER BROWN, OF CHICAGO, ILLINOIS.

PROCESS OF INSTALLING WATER-FRONT WALLS.

1,347,459.

Specification of Letters Patent.

Patented July 20, 1920.

Application filed September 2, 1919. Serial No. 321,164.

To all whom it may concern:

Be it known that I, EDGAR K. HAND, a citizen of the United States, residing at Chicago, in the county of Cook and State 5 of Illinois, have invented new and useful Improvements in Processes of Installing Water-Front Walls, of which the following is a specification, reference being had to the drawings annexed.

10 This invention relates to the process, or method, of installing water front walls, and particularly to the construction and installation of a concrete water front wall which is a continuous mass, and consists of spaced 15 pilasters and panels between said pilasters.

Among the objects of this invention is to obtain a process or method of installing concrete walls on water fronts which will produce a solid construction which is a continuous mass, having no seams, interstices, 20 cracks or apertures through which water can be forced or otherwise caused to flow.

A further object is to obtain a process or method of installing a water front wall 25 which will not be undermined at the lower edges thereof, and from which the backing will not be removed.

In the drawing referred to I illustrate the several members entering into a wall installed by this process or method, in which—

Figure 1 is a perspective of a panel and a pile which are, respectively, adapted to form members in said wall;

Fig. 2 is a side elevation of the pile which 35 is also illustrated in Fig. 1;

Fig. 3 is a top plan view of the upper end, or top, of a wall which has been installed by this process; and

Fig. 4 is a perspective of a member of 40 the nozzle end of the pipe extending longitudinally through the pile.

A reference character applied to designate a given part of the several members illustrated, indicates said part throughout 45 the several figures of the drawing, wherever the same appears.

In carrying out this process I first construct panels of reinforced concrete, as panel A, providing said panels with grooves, 50 as a, a , on the face thereof which comes in contact, as will be hereinafter described, with the piles. I also provide, on the lower side or edge thereof, the bevel edge a^1 , for purposes hereinafter described. For reasons hereinafter disclosed said beveled edge

a^1 does not extend to the ends of said panels; said ends being of uniform thickness the entire depth thereof, as illustrated by end a^2 , Fig. 1. I also leave the upper edge or side of the panels unfinished, as at B, Fig. 1, with the vertically extending reinforcing members b, b , projecting beyond said side B. This method of making panels A, A, permits the placing of a monolithic top or coping, (B¹, Fig. 3), on the wall, as the final step of the herein described process.

An additional step in the carrying out of this process or method of installing water walls is the building up of reinforced concrete piles C, C; each of which piles has em- 60 bedded therein, (by flowing around it a concrete mixture before the same is hardened),

a pipe D. This pipe extends longitudinally through the pile to near the lower end thereof, and extending above said pile at the upper end. The projecting upper end of said pipe D is provided with screw threads, 70 designated by the reference character D¹, in Figs. 1 and 2, to which a hose is attached, as hereinafter recited. At the lower end of pipe D I attach, by means of coupling E, the nozzle pipe F, of novel construction.

Said nozzle pipe includes the member G, which is illustrated in perspective in Fig. 4, 75 said member being driven or otherwise forced into said nozzle pipe F, so as to be

rigidly held therein. Member G is provided with wings or blades g, extending outward from the central hub g¹, and winding spirally at the outer edges g² thereof, 80 around said hub g¹. These blades are

thicker at the lower ends thereof, than at the upper ends, said increase in thickness 85 commencing below the center of said member, and by said thickening I obtain the restricted apertures g³, g⁴, said thickening being on the forward side of the blades, as is indicated at g³, g⁴.

The function of the spiral winding of the several blades g, g, 90 is to produce a whirling motion to water flowing rapidly through said pipe D and from said nozzle end G; and the restricted openings caused by the thickening of the blades g produces great velocity to said flow.

I find in practising this process that one 95 quarter turn of the outer edges g² of said blades g, said turning not being too rapidly made, will so deflect and whirl said water as

to obtain from, say, a two inch pipe, a whirling 100 body of water of approximately four

105 quarter turn of the outer edges g² of said blades g, said turning not being too rapidly made, will so deflect and whirl said water as

to obtain from, say, a two inch pipe, a whirling 110 body of water of approximately four

teen to sixteen inches in diameter when the forward motion thereof is obstructed, as by dirt or mud, under the conditions herein-after set forth.

5 The pile C is provided with rabbets C¹, C¹, and steps C², C², in which rabbets and on which steps, in carrying out this process or method, the ends of panels A, A, are placed.

10 In the making of the pile C I provide longitudinally extending grooves d, d, from one end of said pile to said steps C², C².

H, Fig. 1, represents reinforcing members of the pile C, which extend upward beyond 15 the ends of the pile, for the same purpose as do the reinforcing members b, b, of the panels.

I, Fig. 1, represents a tongue, which by 20 this method or process is driven into groove a, from the upper edge of the panels to the step C²: the function of said tongue being to seal, or partially seal the grooves d, d, in case the panels do not fit closely to the face of the pile adjacent thereto, in the carrying 25 out of the process, or method.

The bevel a¹ on the lower edge of the 30 respective panels A, does not extend to the end of said panels, so that a suitable bearing surface, as at a², is provided, to rest on said step C², and said panel to be thereby 35 well supported. The portion of the pile which is illustrated in the drawing as between the step C² and the lower end of said pile is gradually rounded and decreased in cross section, and said lower end is rounded 40 substantially as is illustrated in Fig. 2.

When a water wall installed by this process is to form a breakwater, and there is believed to be a probability of currents being 45 created in the water coming in contact with the wall, with a liability that said currents may undermine the paneled portion of the wall, and so permit the back fill to be washed out therefrom, the piles used are provided 50 with the jetty or mud sill J, Fig. 2, which is integral with the body of said pile, and suitably reinforced.

I find that the mud sill J, prevents scouring, as it is termed, between the several piles, 55 protecting the lower edges of the panels from being uncovered by earth or mud.

A suitable number of panels A, A, and piles C C being provided, the process of installing the wall is as follows;

55 The piles are successively placed vertically in spaced relation with each other, to correspond with the length of the panels. As each pile is placed in said vertical position it is lowered until the lower end thereof 60 sinks into, or becomes embedded in the bed or bottom of the body of water which will,

when the wall is installed, come in contact with the front thereof. A hose or flexible pipe is then connected to the upper end of 65 pipe D, and water under great pressure, say

not less than one hundred and fifty pounds per square inch, is forced into and through said pipe, and is discharged therefrom through the nozzle pipe F and nozzle G. Said nozzle being made as illustrated in 70 Fig. 4 and hereinbefore described, said water, discharged therefrom, swirls or has a spirally rotary movement, and rapidly removes obstructions under the lower end of said pile, and said pile will thereupon (in 75 nearly every case by its own weight), descend. The operation is continued until the determined descent or sinking of said pile is accomplished. Where it is found that the descent of a pile stops before said determined sinking is accomplished additional weight is placed on the upper end of the pile.

A plurality of piles in spaced relation being positioned, each in the manner above described, a panel A is fitted vertically in place 80 between adjacent piles and permitted to descend, said descent being effected by its weight, until the lower end of the ends thereof are in contact with the steps C², and below the bed or bottom of the water where the 85 wall is being installed. I find in practice it is necessary, occasionally, to use what is termed a portable jet, that is, a nozzle attached to the end of a flexible pipe and to direct by means thereof, a flow of water 90 under pressure onto or against the lower beveled edge a¹, of said panel A, to accomplish the descent thereof to rest on step C².

When the piles and panels are installed, 100 as above described, I find, at times, the contact or fit between the panels and the piles is sufficiently close to allow me to proceed with the next essential step in my process. Where said contact or fit is not sufficiently close the 105 strips or packings I, I, are inserted and driven down into the longitudinally extending passage ways which are obtained by the grooves d, d, and the adjacent faces of the piles. The strips which form the packings 110 I, I, may well be of wood of a size and shape to fit closely in said passage ways. The close fit of the panel to the piles, in the descent thereof to its position on the steps C², C², is facilitated by the beveled edge a¹ of said 115 panel; said beveled edge being on the back or dirt side of said panel.

When the passage ways extending from the steps upward and formed by the walls of the grooves d, d, and so much of the face 120 of the piles as is between the edges of the side walls of said grooves, is sufficiently sealed, either with or without the use of said packing I, said passage ways are grouted.

It will be observed that the piles and 125 panels being positioned as and by the several hereinbefore described steps of this process, said passage ways d, d, form wells which contain considerable water, and to effectively deposit a grout mixture in place 130

at the lower ends of said wells and on said steps, in condition with the elements thereof aggregated and adapted to "set" or crystallize into a solid mass adhering to the walls 5 of said wells, thereby becoming integral therewith, I provide a dehydrated concrete mixture, or grouting, and I convey said grouting in its dehydrated condition to the place in said wells where it is to be deposited, and hydrated. To effect the foregoing, I insert a flexible hose, (shown in cross section in Fig. 3, and designated by the reference character K), in said wells, and to near the bottom thereof, and from 10 said hose I discharge air, under considerable pressure, into said wells in sufficient volume to thereby drive substantially all the water in said wells out therefrom.

Substantially all the water in said wells 20 being driven therefrom by said flow of air under pressure from said flexible hose, I introduce into the air discharged therefrom the dehydrated grouting, to be deposited in said wells. The pressure of the mixture of 25 air and grouting is sufficient to prevent the flow of water into the flexible pipe and to force the grouting discharged from the hose into said wells and into a shallow body of water, if any there be, below the lower end 30 of said flexible hose. On the deposit of the grouting in said wells a separation occurs between said grouting and said air, the grouting settling or sinking below the hose and the air flowing upward in said wells, 35 whether there be sufficient water in the wells below said hose to hydrate the grouting or whether it remains for a brief time in its dehydrated condition. A deposit of said grouting being first made in the manner recited on said step C², as the quantity of said 40 grouting increases the hose is gradually raised, and the air which is released therefrom separating from the grouting, water settles or percolates thereinto, and hydrates it. I find in practice that the sealing of said wells by the strip I is sufficient to enable me 45 to obtain, at the lower ends thereof and above the grouting therein, a pressure which prevents a flow of water into said wells 50 faster than can be held back by the air pressure; and I also find that as soon as slight depth is obtained in the dehydrated grouting deposited in said wells sufficient

water seeps or falls into it to hydrate it. This process of filling said wells with dehydrated grouting is continued until the deposit thereof reaches substantially to the water level therein, and thereafter water is supplied thereto in sufficient quantity to hydrate the grouting. 55

The relative quantity of air under pressure and of the grouting which is discharged from the flexible hose is determined by suitable adjusting means, and the pressure of the air in said hose is variable, depending 60 on the depth of the water in said wells; but as hereinbefore recited, said pressure is at all times sufficient to force the mixture of air and grouting out of said hose and to direct said grouting to where it is required 65 to be deposited, to seal said wells completely and join the panel and piles into a single mass of reinforced concrete. The volume of air supplied is at all times sufficient to convey the grout mixture to and deposit it in 70 said wells, and to prevent its hydration before the discharge thereof from said hose. The clogging of said hose is thereby prevented, and the deposit of said grouting 75 assured. 80

When a water wall is completed by the hereinbefore described process or method, a coping or flooring, (in the case of a dock), is joined to the upper end of the wall, in the usual way. 85

I claim;

The process of grouting wells between bodies of concrete, said wells having water therein, and making said grouting integral with said bodies, which comprises the substantial sealing of the walls of said wells, the expulsion, by means of air under pressure, of substantially all of the water in said wells, the conveying to and discharging thereinto and near the lower ends of said wells, a mixture of air and dehydrated grouting, under pressure sufficient to direct said grouting to said lower ends, subsequently hydrating said grouting, and continuously directing a mixture of air and dehydrated grouting on said continuously advancing grouting in said wells. 95 100

EDGAR K. HAND.
